RESILIENT RAIL FASTENER

George R. Burkhardt, Chicago, Ill.

Application January 19, 1942, Serial No. 427,377

10 Claims. (Cl. 238—349)

This invention relates to rail fasteners of the type which are resilient to permit the rail to partake of the wave motion imparted to it by the passage of rolling stock thereover, and has particular reference to improvements in rail fasteners of this type which comprise an anchor element to be anchored to a support for the rail and a coil spring engaged upon the anchor element between the rail flange and an abutment on the anchor element and reacting from said abutment upon the rail flange to hold the rail yieldably seated upon its support.

One object of the invention is to provide a shoe through which the coil spring acts to exert its holding force upon the rail flange, and to construct said shoe and the anchor element for co-operation in a novel manner to maintain the shoe operatively disposed relative to the rail flange and the anchor element.

Another object of the invention is to form the coil spring for cooperation with the anchor element to insure a proper operative relationship between said spring and the rail flange.

With the foregoing and other objects in view, which will become more fully apparent as the nature of the invention is better understood, the same consists in a resilient rail fastener embodying the novel features of construction, combination and arrangement of parts as will be hereinafter more fully described, illustrated in the accompanying drawings and defined in the appended claims.

In the accompanying drawings, wherein are illustrated specific practical embodiments of the invention, and wherein like characters of reference denote corresponding parts in related views:

Figure 1 is a cross sectional view through a portion of a rail, its support and one practical form of the improved resilient rail fastener, showing the initial step employed in operatively applying said fastener to the rail support and the rail.

Figure 2 is a view similar to Fig. 1 showing the second step employed in operatively applying the resilient fastener to the rail support and the rail.

Figure 3 is a view similar to Figs. 1 and 2 showing the resilient fastener operatively applied to the rail support and the rail.

Figure 4 is a horizontal section on the line 4—4 of Fig. 3; and

Figure 5 is a view similar to Figs. 1 to 3 illustrating a slightly alternative construction.

Figure 6 is a cross section on the line 6—6 of Fig. 5.

Figure 7 is a view similar to Figs. 1 to 3 illus-

trating another alternative embodiment of the invention; and

Figure 8 is a cross section on the line 8—8 of Fig. 7.

According to each of the illustrated embodiments of the invention the improved resilient fastener is designated generally as A, a portion of the base flange of a rail to be fastened is designated as 10, a portion of a tie plate upon which the rail rests is designated as 11, and a portion of a cross tie upon which the tie plate rests is designated as 12.

Also, according to each illustrated embodiment of the invention, the resilient fastener A comprises an anchor element in the form of a pin 13 formed at its lower end to be anchored to the tie plate 11, a resilient element in the form of a coil spring 14 engaged on the upper portion of said pin, and an adjustable abutment element 15 in the form of a nut 16 threaded on the upper end of the pin 13 and from which said spring is designed to react to impose its force upon the rail flange. Moreover, according to the Figs. 1 to 6 embodiments of the invention, the fastener A includes additionally a shoe 15 to be interposed between the lower end of the spring 14 and the upper face of the rail flange 10 and upon and through which the spring 14 is designed to act to impose its force on the rail flange.

At its lower end the pin 13 is provided with an inwardly projecting toe 17, while at a suitable distance above its lower end said pin is provided with an outwardly projecting lug formation 18 the ends of which extend beyond the sides of said pin.

To anchor the thus constructed pin to the tie plate 11, the pin is placed in a downwardly and outwardly inclined position with its lower end aligned with one of the spike holes 19 in the tie plate and then, by downward movement of said pin, its lower end portion is caused to pass downwardly through said spike hole 19 until the toe 17 is disposed below the plane of the bottom face of the tie plate in an accommodating recess 20 provided in the top of the cross tie 12, as shown in Fig. 1. The pin then is swung outwardly to cause the toe 17 to become engaged beneath the tie plate at the inner side of the spike opening, and this outward swinging movement is continued until the lug formation 18 engages the top of the tie plate at the outer side of the spike opening 19, as shown in Fig. 2. Any further outward swinging movement is prevented by the cooperation of the toe 17 and the lug 18 with the tie plate and the pin thus occupies an upwardly and outwardly inclined applied position in which it is inter-

50
55

locked with the tie plate against upward or downward or outward swinging movement relative thereto. In this connection it is pointed out that the spacing of the lug formation 18 from the toe 17 is such that the pin, in its applied position, is disposed at substantially right angles to the plane of the top face of the rail flange 10; also, that the lower end portion of said pin is of substantially rectangular shape in cross section, or at least has flattened sides, or a flattened inner or outer face, for cooperation with one or more of the walls defining the spike opening 19 to hold the pin 13 against rotation.

Before applying the pin 13 to the tie plate, the nut 16 is screwed upwardly along the upper end of said pin to a position, as shown in Figs. 1 and 2, in which it does not interfere with movement of the coil spring 14 and the shoe 15 upwardly along said pin to positions in which they do not interfere with application of said pin to the tie plate. When, however, the pin has been applied, the nut 16 is screwed downwardly to compress the spring 14 and to cause it to act either directly upon the rail flange 10, as in the Figs. 7 and 8 embodiment of the invention, or through the shoe 15, as in the Figs. 1 to 6 embodiments of the invention, to impose a yieldable holding force downwardly upon the rail flange. The intensity of the holding force exerted by the spring 14 is, of course, determined by the amount that the nut 16 is screwed downwardly, and in this connection any suitable means such as a cotter pin or the like may be employed to secure said nut in any desired position of adjustment, the means for this purpose being illustrated in the present instance by way of example as comprising a spring finger 21 carried by said nut for cooperation with the threads of the pin 13.

According to the Figs. 1 to 4 embodiment of the invention the shoe 15 is in the form of a plate, preferably but not necessarily having its inner marginal portion offset downwardly to provide a toe 22 to engage the upper face of the rail flange, and further having a pair of recesses 23 extending inwardly from its outer edge and defining therebetween a tongue 24 which is bent upwardly from the plate to a position at substantially right angles thereto to seat against the inner face of the pin 13 to hold the shoe against outward movement and to guide the same for movement longitudinally relative to said pin and to prevent it from being tilted by the spring 14.

The recesses 23, besides serving to provide the tongue 24, serve to provide a pair of arms 25, 25, one at each side of the shoe 15, and when the tongue 24 is bent upwardly there is provided a space between said arms to accommodate the pin. Thus, in the operative position of the shoe 15 relative to the pin 13, as shown in Figs. 2 and 3 of the drawings, the arms 25, 25 are disposed at opposite sides of said pin, respectively, and cooperate therewith to hold the shoe against side-wise movement from its operative position.

Any suitable means may be provided to prevent rotation of the shoe 15 relative to the pin 13. However, a simple, practical and preferred means for this purpose may comprise a flat face 26 at the inner side of the pin 13 against which the outer flat face of the tongue 24 may bear, as illustrated in the drawings.

Best cooperation of the coil spring 14 with the shoe 15 and the rail flange 10 is obtained by having the terminal end portion of the lowermost coil of said spring disposed in overlying relationship to the portion of said shoe which is

disposed inwardly of the pin 13. Accordingly, to provide for readily obtaining and maintaining this relationship, the lower terminal portion of said spring is bent downwardly to provide a lug 27 to engage one of the side edges of the shoe 15. The lug 27, by cooperation with its related side edge of the shoe 15, holds the spring 14 against rotation, and the relationship of said lug to the terminal end portion of the lowermost coil of said spring 14 and to the said side edge of the shoe 15 is such that when said lug is engaged with the said side edge of said shoe the said terminal end portion of the lowermost coil of said spring is disposed in overlying relationship to the portion of said shoe which is disposed inwardly of the pin 13.

The Figures 5 and 6 embodiment of the invention is the same as the Figs. 1 to 4 embodiment except in respect to the form of the shoe 15 and the manner in which said shoe cooperates with the pin 13. According to the Figs. 5 and 6 embodiment of the invention the shoe 15 is provided with an opening 28 to accommodate the pin 13, and the outer end portion of said shoe is disposed in overlying relationship to the lug formation 18 and rests thereon. Thereby said shoe is supported or fulcrumed at its outer end upon said lug formation for downward swinging movement of its inner end portion into holding engagement with the rail flange by the spring 14. In this connection since, according to the Figs. 1 to 4 form of the invention, the lug 18 is not required to support the outer end of the shoe 15, said lug, according to said form of the invention, need not extend beyond the sides of the pin 13 but may be of any desired width. In fact, according to the Figs. 1 to 4 form of the invention, a shoulder of any suitable type may be employed in lieu of the lug 18 to serve the purpose of said lug.

To hold the shoe 15 of the Figs. 5 and 6 embodiment of the invention against rotation relative to the pin 13, said shoe may be flanged downwardly at its outer end, as indicated at 29, for cooperation with the outer face of the lug 18.

The Figs. 7 and 8 embodiment of the invention is generally the same as the Figs. 1 to 6 embodiments except that the toe 17 and the lug formation 18 are designed to hold the pin 13 in a vertical position, instead of an upwardly and outwardly inclined position, and except that the terminal end portion of the lowermost coil of the spring 14 acts directly against the rail flange 10 instead of through a shoe. According to the Figs. 7 and 8 embodiment of the invention the terminal portion of the lowermost coil of the spring may bear against the rail flange and not against the lug formation 18, or against both the rail flange and said lug formation. In the latter event the outer portion of its lowermost coil obviously will tend to fulcrum upon the lug 18 to insure proper holding cooperation of the inner portion of its lowermost coil with the rail flange. In either case, the terminal end portion of the lowermost coil preferably is bent downwardly, as indicated at 30, to overlie and cooperate with the outer edge of the lug formation 18 to hold the spring 14 in a desired position of rotation.

While the anchor element 13, according to each of the illustrated embodiments of the invention, is in the form of a pin for interlocking cooperation with a tie plate, it is manifest that said anchor element may, if desired, be in the

form of a spike to be driven or screwed into the cross tie 12.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. Means for resiliently fastening a rail upon a support, said means comprising an anchor element to be anchored to the support, said anchor element including a shank to extend above the support and the base flange of the rail, an abutment on said shank, a shoe to engage the rail flange, a coil spring on said shank between said abutment and said shoe to react from the former upon and through the latter to impose its force upon the rail flange, said shoe and shank having means cooperating directly with each other to hold said shoe against rotation relative to said shank, and a downwardly extending lug on the lower end of said spring for engagement with an edge of said shoe to hold said spring against rotation in either direction from a predetermined position of rotation relative to said shoe.

2. Means for resiliently fastening a rail upon a support, said means comprising an anchor element to be anchored to the support, said anchor element including a shank to extend above the support and the base flange of the rail, an abutment on said shank, a shoe to engage the rail flange, a coil spring on said shank between said abutment and said shoe to react from the former upon and through the latter to impose its force upon the rail flange, and a tongue extending upwardly from said shoe and disposed against the inner side of said shank to hold said shoe against downward and outward tilting movement relative to said shank under the force exerted thereon by said spring.

3. Means for resiliently fastening a rail upon a support, said means comprising an anchor element to be anchored to the support, said anchor element including a shank to extend above the support and the base flange of the rail, an abutment on said shank, a shoe to engage the rail flange, and a coil spring on said shank between said abutment and said shoe to react from the former upon and through the latter to impose its force upon the rail flange, said shoe comprising a plate for contact at its inner end with the upper face of the rail flange and having in its outer end portion a medial recess accommodating said shank and providing a pair of arms disposed to opposite sides of said shank, respectively, whereby said shoe is held against sidewise movement relative to said shank, said shank having a flat inner face and said shoe further having a tongue extending upwardly therefrom at substantially right angles thereto into said spring and disposed against said flat face of said shank, whereby said shoe is held against tilting downwardly and outwardly under the force exerted thereagainst by said spring.

4. Means for resiliently fastening a rail upon a support, said means comprising an anchor element to be anchored to the support, said anchor element including a shank to extend above the rail support and the base flange of the rail, a lug formation on said shank, an abutment on

said shank, a shoe for holding contact at its inner end with the rail flange, and a coil spring on said shank between said abutment and said shoe to react from the former upon and through the latter to impose its force upon the rail flange, the outer end portion of said shoe resting upon said lug formation and being supported thereby against downward movement and for rocking movement whereby its inner end portion is caused by said spring to be urged downwardly into holding cooperation with the rail flange.

5. Resilient rail fastening means as set forth in claim 4 in which the shank and the shoe are formed for cooperation to hold the shoe against outward and sidewise movement and rotation relative to the shank.

6. Resilient rail fastening means as set forth in claim 4 in which the shoe is provided with a lip for cooperation with the lug formation on the shank to hold the shoe against rotation relative to the shank.

7. Means for resiliently fastening a rail upon a support, said means comprising an anchor element to be anchored to the support, said anchor element including a shank to extend above the rail support and the base flange of the rail, a lug formation on said shank, an abutment on said shank, and a coil spring on said shank between said abutment and the rail flange reacting from the former upon the latter, said spring having a portion thereof cooperating with said lug formation to hold said spring in a predetermined position of rotation relative to the rail flange.

8. Means for resiliently fastening a rail upon a support, said means comprising an anchor element to be anchored to the support, said anchor element including a shank to extend above the rail support and the base flange of the rail, a lug formation on said shank, an abutment on said shank, and a coil spring on said shank between said abutment and the rail flange reacting from the former upon the latter, said spring having its lower terminal end portion directed downwardly into overlying relationship to the outer edge of said lug formation thus to cooperate with said lug formation to hold said spring in a predetermined position of rotation relative to the rail flange.

9. A resilient fastener for a rail comprising, in combination with a tie plate interposed between the rail and a supporting cross tie and having therein an anchoring pin accommodating hole, an anchoring pin having its lower end portion disposed in said hole, a toe on the lower end of said pin extending inwardly therefrom and underlying the tie plate whereby the pin is held against upward movement relative to said plate, a lug formation on said pin extending outwardly therefrom and engaging the top of the tie plate whereby the pin is supported in a predetermined position against outward rocking movement relative to the tie plate, said lug formation being elongated and extending beyond each side of said pin to assist in supporting said pin against sidewise rocking movement relative to said tie plate, an abutment element on the upper end portion of said pin, and a coil spring surrounding said pin and by reactance from said abutment element exerting a yieldable holding force downwardly upon the rail.

10. A resilient rail fastener as set forth in claim 9 in which the coil spring directly engages the rail flange.

GEORGE R. BURKHARDT.
